UNITED STATES PATENT OFFICE.

JACOB WINKLER, OF NEW YORK, N. Y., ASSIGNOR TO AUTO PEDAL PAD CO., OF NEW YORK, N. Y., A CORPORATION OF NEW YORK.

DESIGN FOR AN AUTO PEDAL-PAD.

48,341.

Specification for Design.

Patented Dec. 21, 1915.

Application filed March 23, 1915. Serial No. 16,494. Term of patent 7 years.

To all whom it may concern:

Be it known that I, JACOB WINKLER, a subject of the Emperor of Germany, and a resident of the city of New York, borough of Brooklyn, in the county of Kings and State of New York, have invented a new, original, and ornamental Design for an Auto Pedal-Pad, of which the following is a specification, reference being had to the accompanying drawing, forming part thereof, in which—

I claim:

The ornamental design for an auto pedal pad, as shown.

JACOB WINKLER.

Witnesses:

C. BRADWAY,
G. H. EMSLIE.
